UNITED STATES PATENT OFFICE.

CHARLES EDWARD ELLIS, OF BROOKLYN, NEW YORK, ASSIGNOR TO RAPID ADDRESS-
ING MACHINE COMPANY, A CORPORATION OF NEW YORK.

FILING CARD.

Application filed August 12, 1925. Serial No. 49,683.

While my invention relates to filing cards generally it is particularly designed for use on address bearing stencil cards which are employed as a part of printing apparatus 5 for addressing envelopes and other matter when not filed away in their trays or other filing receptacles.

Briefly stated, the invention consists in providing such filing cards with a depressed 10 panel area along a portion of their faces at their upper edges, whereby much greater facilities for, and convenience in, handling and indexing such cards in their filing cases, and other advantages are secured.

15 The best form of apparatus at present known to me embodying my invention and certain modifications thereof are illustrated in the accompanying sheet of drawings in which—

20 Fig. 1 is a perspective face view of a stencil card embodying my invention.

Fig. 2 is a face view of the upper portion of the card shown in Fig. 3 with movable index clips attached.

25 Fig. 3 is a cross section on line 3—3 of Fig. 2 through a series of cards as same would be placed in a filing tray or drawer.

Fig. 4 is a detail view of the upper portion 30 of a similar card having index notches and a modified form of index clip mounted thereon, and

Fig. 5 is a cross section on line 5—5 of Fig. 4.

Throughout the drawings like reference 35 characters indicate like parts.

1 is a pasteboard frame of a standard form of stencil card for use in addressing machines having a cut-away portion across which a sheet of paper 2, forming the stencil section, is pasted. 3 is a depressed panel area along the upper edge of said card frame 1, preferably not extending lengthwise to the end of the card, but leaving the end portions of the frame 1^a and 1^b of normal thickness. 45 These panels can be conveniently formed by stamping the cardboard to a greater density and less thickness over the predetermined area. That is to say, the panel area 3 is formed by making that portion of the card frame thinner than the adjacent portions of said frame. 4, 4, represent index notches of predetermined location along the upper edge of the card, which may be used if desired, and 5, 5, represent 50 bifurcated clips usually formed of thin metal

adapted to rest on and straddle the thinner portion of the upper edge of the card which results from the formation of the panel 3, of depressed area, as above described. To realize the more important 60 features of the invention these clips 5 should be formed of a material having a thickness not greater than the depth of the depression of the panel 3. Usually the thickness of the clip material is made equal to the depth of 65 said depression. In any case the thickness of each leg of the clip preferably should not exceed the difference in thickness between the general card frame 1 and the panel portion 3 thereof. Thus if the card frame 1 is 70 .07 inch thick, and the panel portion 3 is .04 inch thick, the metal out of which the clips 5 are made preferably should not be over .03 inch thick. As a result, one leg of the 75 clip nests in the depression formed by the panel in the card on which it is mounted and the other leg in the corresponding depression in the next card back of that on which it is mounted when a series of cards are collected in a tray, (the clips on adjacent cards being, of course, arranged in 80 staggered relation one to another), said depressed panel areas forming spaces 7, 7, between adjacent cards, as shown in Fig. 3, or are stacked in a magazine. As the result of this, these clips can be mounted on 85 such of the cards as may be necessary to carry out the indexing system without in any way interfering with the cards lying snugly one against another in perfect parallelism as shown in Figs. 2 and 3, where 5, 5^a, 5^b, 5^c and 5^d represent a plurality of clips, one mounted on each of a series of cards assembled for deposit in a tray, not shown.

The modified form of clip 5, shown in 95 Figs. 2 and 3 has an upward extension to render it more easily visible.

If index notches 4, 4, are used, the clips 5 should preferably be made of a width sufficient to bridge said notches and in such 100 case said clips may be used as a means for covering some or all of the index notches, thereby modifying their indexing functions and, adding to the flexibility and comprehensiveness of any given indexing system. 105 The index clips 5 may, of course, be given different colors to form the necessary indexing distinctions and printed index matter may appear on the faces of the cards near their upper edges where it will be visi- 110

ble on slightly separating the same. In fact nearly all existing indexing devices may be used in combination with my invention and their operation facilitated and further improved by it.

Among the advantages of the invention may be mentioned the following: Independently of any indexing feature the depressed panel areas are advantageous in the case of filing cards because the creation of the spaces 7, 7, shown in Fig. 3 between successive cards tends to break the slight vacuum which exists between the adjacent faces of every two cards if perfectly flat, and enables the user to more easily separate the individual members of a set of these cards laid closely together in a file tray. The same space adds somewhat to the visibility of any printed index matter 8 when the same is placed in the depressed panel area. When index clips are used, the thicker end portions 1^a and 1^b of the cards act as stops limiting the sliding motion of the clips and (in the case of address bearing stencil cards) prevent the clips getting near enough to the end of the cards to stick in the guides of the addressing machine. When the depressed panel areas are formed by stamping, as above described, this tends to force more closely together the layers forming the cardboard and the liability of splitting the card when endeavoring to apply the metal clip is correspondingly reduced and the application of such clips generally facilitated. The invention also permits the application of the index clips to stencil cards which are to be used in addressing machines because it permits a tall stack of such cards to all lie in horizontal planes in the vertical card magazine. Heretofore, it has not been practical to use metal clips on such stencil cards because such clips, being all located along the edges on one side of the cards, produce a cumulative thickening action at that edge which prevented the cards lying properly in the magazine. The depressed panel section, by diminishing the adhesion of one card to another, also facilitates the pulling out of the bottom card of the stack in such a magazine by the card feeding mechanism which delivers the cards successively to the inking mechanism in an addressing machine. Also the presence of the depressed panel area tends to cause an operator picking up a series of such cards out of a filing tray to grasp any given bunch of cards, which he desires to remove, at a point well down toward the center and thereby secure a firm grip instead of grasping them along the upper edges with the consequent possibility of the interior cards of the bunch dropping out because they are insecurely held.

Various changes could be made in the details of construction above described as embodying the preferred form of my invention,

and various of the novel features described and claimed could be employed without including all of them in any one embodiment.

Having described my invention, I claim:

1. As a new article of manufacture, a filing card having a substantially straight upper edge and a depressed panel area along the upper portion of its face, extending inwardly from said upper edge.

2. As a new article of manufacture, a filing card having a substantially straight upper edge and a depressed panel area along the upper portion of its face, extending inwardly from said upper edge and end portions of normal thickness limiting the lateral extension of said panel area.

3. The combination of a filing card having a depressed panel area along the medial portion of the upper edge of its face, the ends of said edge portion being the full thickness of the card and a U-shaped index clip mounted on and straddling the thinner edge portion so formed on the card, whereby said end portions serve as stops to prevent sliding said clip beyond said depressed panel area.

4. The combination of a filing card having a depressed panel area along the upper edge of its face and a bifurcated index clip mounted on and straddling the thinner edge portion so formed on the card, each leg of said clip having a thickness not exceeding the depth of the depression forming said panel area, whereby, when a series of such cards provided with such clips are stacked together, the legs of said clips may rest in the free spaces formed by said depressed panel areas.

5. The combination of a filing card having a depressed panel area along the medial portion of the upper edge of its face, the ends of said edge portions being of the full thickness of the card and a U-shaped metal index clip mounted on and straddling the thinner edge portion so formed on the card, each leg of said clip having a thickness not exceeding the depth of the depression forming said panel area, whereby, when a series of such cards provided with such clips are stacked together, the legs of said clips may rest in the free spaces formed by said depressed panel areas, but are limited in their movements by the thicker end portions of the card edges.

6. The combination, with a filing card having a depressed panel area along its upper edge and index notches cut in said edge, of a bifurcated clip of a width sufficient to bridge said notch mounted on and straddling said upper edge, said clip being formed of sheet metal of a thickness substantially equal to the depth of the depression forming said panel, whereby, when a series of such cards provided with such

clips are stacked together, the legs of said clips may rest in the free spaces formed by said depressed panel areas.

7. As a new article of manufacture, a filing card of substantially rectangular cross section of substantially uniform thickness along all its edges except throughout a portion of its upper edge, along which portion

the card has a panel composed of a less thickness of material than the remainder of ¹⁰ the card edges, said panel extending inward from said edge a substantial distance; whereby a removable index clip may be conveniently mounted upon said portion of reduced thickness.

CHARLES EDWARD ELLIS.
